UNITED STATES PATENT OFFICE.

DURAND A. REESE, OF PHILADELPHIA, PENNSYLVANIA.

DESIGN FOR A BADGE.

SPECIFICATION forming part of Design No. 16,367, dated November 3, 1885.

Application filed August 7, 1885. Serial No. 173,872. Term of patent 7 years.

To all whom it may concern:

Be it known that I, DURAND A. REESE, a citizen of the United States, residing in the city and county of Philadelphia, State of Pennsylvania, have invented and produced a new and original Design for Badges, of which the following is a specification, reference being had to the accompanying engraving, forming part thereof.

10 The leading features of my design are the cross mallets having scroll and plates depending therefrom, a flag, and a shield having a square, compasses, and a mechanic's arm thereon.

15 A represents a shield, on the face of which are the following characteristics: the representation of a square, B, compasses C, and an

arm, D, with a hammer, E, held in the hand thereof, known as the "mechanic's arm," said parts comprising the lower part of the badge. 20 F represents a flag, at the top of which are crossed gavels G and a scroll, H, and on the face of the same a plate, J, a scroll, K, a plate, L, and suspension-chains M, said parts comprising the upper part of the badge. 25

I claim—

A design for a badge, consisting of a shield, a square, a compasses, a mechanic's arm, a flag, cross gavels, scrolls, and plates, as shown and described.

DURAND A. REESE.
